UNITED STATES PATENT OFFICE.

DAVID L. LINDQUIST, OF HARTSDALE, AND GEORGE W. LAUTRUP, OF YONKERS, NEW YORK, ASSIGNEES TO OTIS ELEVATOR COMPANY, OF JERSEY CITY, NEW JERSEY, A CORPORATION OF NEW JERSEY.

ELECTRIC ELEVATOR MACHINE.

Application filed May 23, 1923. Serial No. 640,832.

Our invention relates to an improved main and auxiliary drive electric elevator machine.

In the combined main and auxiliary drive electric elevator machine of the self-leveling type for gearless traction elevators, the machine comprises a driving sheave directly connected to the motor shaft of the main motor and operatively connected through friction mechanism and worm gearing to the shaft of the auxiliary drive motor, the latter having a brake associated with it.

One feature of the invention is the provision of such mechanism which is of simple and compact construction and which is reliable in operation.

Another feature is the provision of such mechanism in which lost motion is eliminated, in which wear is reduced to a minimum and which may be readily adjusted.

Other features and advantages will be apparent from the following description and appended claims.

In the drawings:

Figure 1 is an elevation view of one side of the combined machine.

Figure 2 is a plan view of the machine.

Figure 3 is an enlarged vertical cross-sectional view of the machine.

Figure 4 is a view of the friction mechanism as seen from the side of the machine by a vertical cut through the casing.

Figure 5 is an enlarged view of a part of Figure 4.

Figure 6 is another view of the friction mechanism as seen from the machine side, but only partly assembled.

Figure 7 is an end view of Figure 6.

Similar reference characters and numerals refer to similar parts throughout the several views.

The combined elevator machine in its integral entirety is mounted on a bed plate 1, common to both the main and auxiliary machines. In the fact of both machines being mounted on one and the same bed plate, alignment of the two machines with each other and those parts of the two machines combined with each other or mounted on the bed plate is thereby maintained and also with the utmost rigidity. There are main bearings and bearing stands, 2 and 9, and 3 and 10, respectively, mounted on the bed plate which support the main motor and in part the friction mechanism B. It is on these bearings and

stands that the load is concentrated. In the case of our invention, only two beams are required to support the common bed plate and combined machines, one of these beams designated 4' being shown in Figure 1, the combined machine as an integral apparatus being placed on the two beams so that the bearing stands, 3 and 10, are directly over them. The load on the machine being concentrated on the bearings and the stands being directly over the two sets of beams, it will be appreciated that, consequently, if any deflection of the two sets of beams occurs which may not be avoided, there will be the least tendency to distort the bed plate or strain the alignment of the two machines with each other.

The main motor A has the customary field frame, 5, bolted to the bed plate, and pole pieces of the usual construction, and field coils, 7, of a new construction which combines maximum ventilation and radiation and are finished off in appearance. Brushes 11 are carried by arms 8 of the brush rigging. The main motor A has a hollow cast steel armature shaft, 12, which serves as the elevator driving shaft for both the main and auxiliary motors, as will appear hereinafter. The two ends of the shaft are journaled in the journal bearings, 2 and 9, of the self-aligning type lined with high grade babbitt and lubricated by means of oil chains. The bearings are made as oil tight as possible and are provided with oil gages (not shown). The journal bearings, 2 and 9, are supported in the two main bearing stands, 3 and 10, and bolted to the bed plate; one of the stands is at the edge or near the edge of one side of the bed plate and the other stand is between a driving sheave C and the friction mechanism B, hereinafter described. The relative positions of the two main bearing stands is plainly shown in Figures 2 and 3. The armature laminations, 13, and commutator, 14, are all securely fastened to the hollow armature shaft. It will be observed, see Figure 3, that the commutator and the bearing, 2, for one end of the armature shaft are let into each other, as it were, which enables the length of the machine to be lessened in effect as it were to the extent of the distance that these two parts are let into each other. On the other end of the armature shaft near its middle there is firmly secured thereto a driving or hoisting sheave C. At the end of the

armature shaft, next to the sheave, is a friction pulley, or wheel, 16, securely fastened to the end of the shaft by bolts, 17. The peripheral surface of the friction wheel is 5 adapted to be engaged by a pair of friction shoes, 18, when applied to its peripheral surface in the operation of the elevator. Each friction shoe is pivoted at 19 to its corresponding operating arm 20, and each arm is pivoted by pins, 21, to a casing, 22, which is adapted to revolve about the axis of the armature shaft and covers the entire friction mechanism. The operating arms are of cast steel, and the friction shoes are lined with 15 asbestos metallic friction block material which is practically incompressible and has a high coefficient of friction which remains almost constant over a wide range of speed of the friction wheel, temperature and wear. 20 The casing 22 has hand holes 68' in it, see Figure 7, through which access to the friction mechanism is had to adjust it. A set screw, 23, in each operating arm is used to adjust the friction shoe to the surface of the friction wheel in order that the curved surface of the shoe may adapt itself to the curved surface of the periphery of the wheel. There is a bolt, 24, in each operating arm and fastened to its respective shoe and having 25 a spring, 25, each set in a cut-out portion, 26, of the arms. Thus the shoe to which each bolt is fastened is pulled against the set screw, holding the shoe fixed. There is an abutting stud, 27, held by and between the 30 operating arms at their pivot ends, and which has an expansion spring, 28, and nuts 15 thereon and is adapted by the expansion of the spring to take up any lost motion that may occur between the arms and their pivot pins, 21, by reason of the journal bearings of the arms or their pins wearing away. At the opposite ends of the operating arms are powerful helical springs, 29, which are adapted to act through the arms on the shoe 35 of each, tending to apply or force the shoes into frictional engagement with the friction wheel, 16. The springs are held on a rod, 30, in cut-out portions, 31, of the arms, the rod having adjusting nuts, 32, thereon. To the 40 operating arms, 20, at their free or spring ends, so to speak, are loosely pivoted at 33 adjusting levers, 34. There is a set screw, 35, in each arm for adjusting its adjusting lever. Each adjusting lever, 34, has a roller, 36, within it, and each roller is held by a pin, 37, in its lever. There is a wedge shaped cam, 38, having inserts, 39, for bearing against the rollers, 36, which cam is adapted to be moved between the rollers, and thereby move 45 the adjusting levers in opposite directions, the movement being transmitted to the operating arms, and they acting against their springs, 29, by their movement effect the release of the friction shoes from engagement 50 with the friction wheel, 16. The wedge shaped cam, 38, is a part of a movable combined magnet arm and core, 40, which is hinged by a pin, 41, to an end plate, 42, of the revoluble frame or casing, 22, of the friction mechanism, and its swinging motion is 55 limited by a stop on said end plate. The stop consists of a rod, 43, one end fast in the plate, 42, and the other end passed loosely through the magnet arm and core, 40, with an adjusting nut, 44, on its free end and a coiled spring, 45, on the rod between the magnet arm and nut limits its outward movement when it is released. A kick-off spring, 46, in the end plate, 42, helps in the operation of 60 releasing the combined magnet arm and core, 40. A stationary magnet, 47, held in a combined casing and stand, 48, is adapted to operate the combined magnet arm and core, 40, to release the friction shoes, 18, from the friction wheel, 16, the said magnet when energized attracting the combined magnet arm and core at its core part, it having a cone, 49, formed thereon which moves in a recess, 50, in the stationary core, 51, of the magnet formed for its reception. In Figure 3 the arm and core, 40, are shown in position when attracted by the magnet, 47. It will be observed that an air gap is shown between the stationary magnet and magnet arm and core or in other words that there is no mechanical contact between the stationary magnet and the magnet arm and core, which means that the magnet arm and core are free at all times to revolve without having mechanical contact with any part of the stationary magnet. The lack of contact between the magnet arm and core and the magnet is ensured by having the magnet arm take up against the end plate, 42. It is obvious that this arrangement or construction eliminates any wear in transmitting the 65 mechanical force from the stationary magnet mechanism to the friction mechanism, which is the case with all constructions where both magnet and armature core are fastened to a stationary stand and the force from the magnet armature is transmitted mechanically through sliding members to the friction mechanism. With the above parts and their relative arrangement, it is plain that a desired or suitable clearance can be established between the wheel and shoes, the amount of which 70 clearance is determined upon in the initial adjustment of the shoes to the wheel. It is also plain that when wear between the wheel and shoes occurs that the amount of clearance between wheel and shoes is changed or increased from the initial or original clearance established, but that the initial or original amount of clearance can be re-established by simply backing out the adjusting screws 75 in the operating arms 20, thereby allowing the free ends of the arms to approach each other to allow for a proper clearance between the wheel and shoes. By that means of adjustment the set or adjusted position between 80 85 90 95 100 105 110 115 120 125 130

the armature core and the stationary magnet is maintained without disturbance. It will be perceived of course that the adjustment for proper clearance can also be made by adjusting the stop comprising the rod, 43, etc. The arm and core, 40, when attracted by the winding moves a rod, 52, to operate a switch arm, 53, to separate its contact, 54, from the other contact, 55, of the switch. A spring, 57, on the switch returns the switch arm to closed position when the magnet, 47 releases its hold on the armature and core, 40, and its pressure on the rod, 52, to hold the switch open. The friction mechanism just described is designed to have the utmost rigidity and perfection of operation, and thus insure its greatest efficiency. As already stated, it rotates as a whole; but the magnet core, 51, and magnet winding, 47, are stationary and do not rotate. The casing, 22, rotates over a surface, 58, on the bearing stand, 10. The end plate, 42, which is fastened to the casing by bolts, 59, as shown in Figure 7, rotates over a surface, 60, on the magnet winding casing and stand, 48. The magnet winding casing and stand serve also in part as a cover for a gear, 61, on the casing, 22, an additional cover, 62, covering the other part of the gear, and also a pinion gear, 63, with which said gear, 61, meshes. The observation was made above that in the embodiment of our invention as to both the structural design and relative arrangement of the commutator 14 and bearing 2, for one end of the armature shaft, that they are tucked or let into each other as it were, thereby and to the extent that they are let into reducing the length of the machine. It is to be observed also that the hoisting sheave or drive wheel, C, is placed as close to the armature laminations as good practice will allow, and the bearing for the revolving frame is let into the drive wheel as much as possible, whereby to the extent of the distance thus gained shortening that end or length of the armature shaft, and consequently the length of the machine. Again it will be noted that the revolving frame completely overhangs the friction wheel or pulley, and operating arms and friction shoes and partially the releasing magnet, the said relative arrangement of each and all of said elements to reduce the total length of the machine to bring its length within the distance from the centers of the average hatchways for this type of machine with its necessary length involved in its necessary load duty for the given job. The pinion gear, 63, is fast on a stud shaft, 64, journaled in a frame, 65, extended from the magnet winding casing and stand, 48, and like it is securely bolted to the bed plate. The pinion gear is a "fibroid" pinion, accurately cut to mesh with the gear, 61, on the revoluble casing. The use of "fibroid" for the pinion gear insures noiseless operation of the gear,

which moves at slow speed. As before stated, the gear is covered with a gear guard or casing, which serves to avoid accidents to the person, and also serves to improve the general appearance of the machine. On the 70 opposite end of the shaft carrying the pinion gear is fast thereon a worm gear wheel, 66, which is also covered with a gear guard or casing. Meshing with the worm gear wheel, 66, is a worm enclosed in a housing, and fast 75 on the end of a shaft, 68, of the armature (not shown, but conclusively presumed) of a motor D, which is securely bolted to the one and same bed plate to which the main hoisting motor A is fastened, as already related. The 80 motor D is a slow speed motor, and serves as the micro-drive motor for the elevator, and also as the motor for automatically leveling the elevator car with a floor landing. When the friction shoes are applied to the friction 85 wheel on the main motor armature shaft and the micro-drive motor, D, is operated, it serves to operate the drive pulley or sheave and the elevator. A brake E is for stopping the motor D and the machine. 90

The friction mechanism serves a double purpose in bringing the car to rest at a landing in that it first acts as a brake to bring the car to a low speed and then as a clutch for connecting the leveling motor D to the driving machine C. 95

When stopping the car between floors, the friction shoes 18 are prevented from rotating by their connections through gear 61, pinion 63, worm wheel 66 and worm to brake E, 100 which is in applied position. Consequently, upon the deenergization of magnet winding 47 so that shoes 18 may engage the friction wheel 16 the car will be brought to rest by the braking action of the friction mechanism B. 105

The leveling machine can be used to marked advantage for the operation of lifting safes. The entire operation may be made with the auxiliary motor. If it be found that the 110 friction mechanism is not set tight enough to lift the safe, all that need be done is to set the friction mechanism sufficiently tight to lift the safe. In the usual elevator the safe may be lifted, but when the elevator is stopped, it 115 may be discovered that the brake will not hold the car; whereas, in the case of the leveling elevator it is plain that, if the friction mechanism is sufficiently tight to lift the safe, it is necessarily sufficiently tight to hold the safe 120 when the elevator stops; therefore, it is perceived that the leveling elevator has a marked superiority for lifting safes. 125

Having thus described our invention, what we claim as new and desire to secure by Letters Patent of the United States is:

1. In combination, a rotatable drum, a pivoted arm, a friction shoe carried by said arm for cooperation with said drum, and resilient means associated with the pivoted end of said 130

arm for taking up any lost motion of the arm on its pivot.

2. In combination, a rotatable drum, friction shoes for cooperating with said drum, pivoted arms for supporting said shoes, and a spring pressed rod inserted between the pivoted ends of said arms to take up any lost motion of the arms on their pivots.

3. In combination, a rotatable drum, a pivoted arm, a friction shoe pivoted on said arm for cooperation with said drum, and resilient means for causing said shoe to exert a pressure on its pivot in a direction away from the drum.

15 4. In combination, a rotatable drum, a pivoted arm, a friction shoe pivoted on said arm for cooperation with said drum, means for adjusting said shoe to the curvature of said drum, and resilient means for yieldingly maintaining said shoe in its adjusted position and for causing said shoe to exert a pressure on its pivot point in a direction away from said drum.

25 5. In combination, a rotatable drum, a pivoted arm, a friction shoe pivoted on said arm for cooperation with said drum, a screw extending through said arm into abutting relation with said shoe on one side of the pivot point for said shoe, said screw being adjustable to adjust the shoe to the curvature of said drum, a rod extending through said arm and secured at one end to said shoe between said screw and the pivot point for said shoe, a retainer on the other end of said rod, and a compression spring arranged on said rod between said arm and said retainer to yieldingly maintain said shoe in its adjusted position in abutting relation with said screw and to cause said shoe to exert a pressure on its pivot point in a

40 direction away from said drum.

6. In combination, a drum, a casing, a pair of friction shoes for cooperating with said drum, an operating arm for each shoe, said arms being pivotally mounted in said casing, an armature pivotally mounted in said casing, said armature being adapted upon movement about its pivot to operate said arms to move said shoes with respect to said drum, said casing, armature, arms and shoes being rotatable as a unit, and a stationary magnet for causing said movement of said armature about its pivot.

45 7. In combination, a drum, a casing, a pair of friction shoes for cooperating with said drum, an operating arm for each shoe, said arms being pivotally mounted in said casing, an armature pivotally mounted in said casing, said armature being adapted upon movement about its pivot to operate said arms to move said shoes with respect to said drum, said casing, armature, arms and shoes being rotatable as a unit, and a stationary magnet for causing said movement of said armature about its pivot, the armature and magnet being arranged relative to each other so as to

prevent mechanical contact of the armature with any part of the magnet at all times.

8. In a combined main and auxiliary drive machine for an elevator car; mechanism for connecting the auxiliary drive machine and the car, said mechanism comprising, a rotatable drum connected to the car, a pair of friction shoes for cooperating with said drum, a pivoted operating arm for each shoe, means connecting said auxiliary drive machine and said arms to permit said auxiliary drive machine to rotate said arms and their respective shoes and therefore said drum when said shoes are in engagement therewith; a pivoted armature mounted to rotate with said arms, said armature upon being moved about its pivot causing the operation of said arms to release said shoes from said drum; and a stationary magnet for causing said pivotal movement of said armature.

85 9. In a combined main and auxiliary drive machine for an elevator car; mechanism for connecting the auxiliary drive machine and the car, said mechanism comprising, a rotatable drum connected to the car to drive the same, a casing connected to said auxiliary drive machine to be driven thereby, a pair of friction shoes for application to the periphery of said drum, an operating arm for each of said shoes, said arms being pivoted to said casing, and actuator springs for applying said shoes to said drum; a magnet; and an armature hinged to said casing to be operated by said magnet to move said arms about their pivots to release said shoes from said drum against the force of said actuator springs, said casing wholly enclosing said drum, shoes, arms, springs and armature and partially enclosing said magnet.

100 10. In combination, a rotatable drum, a pair of friction shoes for cooperating with said drum, an operating arm for each shoe, actuator springs for applying said shoes to said drum, a member movable in one direction to operate said arms to effect the release of said shoes from said drum against the force of said actuator springs, said member having only contact engagement with said arms and being moved in the opposite direction by said springs upon their operation to apply said shoes to said drum, and a yielding stop for limiting the movement of said member in the opposite direction.

105 11. In combination, a rotatable drum, a pair of friction shoes for cooperating with said drum, an operating arm for each shoe, actuator springs for applying said shoes to said drum, a pivoted member acting through said arms to release said shoes from said drum against the force of said actuator springs, said member being swung about its pivot by said actuator springs upon their operation to apply said shoes to said drum, and a yielding stop for limiting the movement of said member upon its being swung by said springs.

12. In combination, a rotatable drum, a pair of friction shoes for cooperating with said drum, an operating arm for each shoe, actuator springs for applying said shoes to said drum, a pivoted member acting through said arms to release said shoes from said drum against the force of said actuator springs, said member being swung about its pivot by said actuator springs upon their operation to apply said shoes to said drum, and an adjustable yielding stop for limiting the movement of said member upon its being swung by said springs. 10
13. In combination, a rotatable drum, a pair of friction shoes for cooperating with said drum, a pivoted arm for each shoe, actuator springs for applying said shoes to said drum, a pivoted armature adapted, upon being swung about its pivot to effect the release of said shoes from said drum against the force of said actuator springs, a magnet adapted upon energization to swing said armature about its pivot to effect the release of said shoes from said drum, said actuator springs causing said armature to be swung back about its pivot upon the deenergization of said magnet in causing said shoes to be applied to said drum, and an adjustable spring stop to limit the movement of said armature upon its being swung back by said actuator springs. 20
14. In combination, a rotatable drum, a pair of friction shoes for cooperating with said drum, a pivoted arm for each shoe, actuator springs for applying said shoes to said drum, a pivoted armature adapted, upon being swung about its pivot to effect the release of said shoes from said drum against the force of said actuator springs, a magnet adapted upon energization to swing said armature about its pivot to effect the release of said shoes from said drum, said actuator springs causing said armature to be swung back about its pivot upon the deenergization of said magnet in causing said shoes to be applied to said drum, and an adjustable spring stop to limit the movement of said armature upon its being swung back by said actuator springs. 30
15. In combination, a drum, a pair of friction shoes for cooperation with said drum, an operating arm for each shoe, an armature adapted upon actuation to operate said arms to move said shoes with respect to said drum, said shoes, arms and armature being rotatable as a unit, a stationary magnet for actuating said armature, a switch, and means actuated by said armature for causing operation of said switch. 40
16. In combination, a drum, a pair of friction shoes for cooperation with said drum, an operating arm for each shoe, an armature adapted upon actuation to operate said arms to move said shoes with respect to said drum, said shoes, arms and armature being rotatable as a unit, a stationary magnet for actuating said armature, said magnet having an operating coil, a switch adapted upon opening to reduce the value of the current supplied to said coil, and a rod operated by said armature, upon the actuation of said armature by said magnet, to open said switch. 50

In testimony whereof, we have signed our names to this specification.

DAVID L. LINDQUIST.
GEORGE W. LAUTRUP.
